UNITED STATES PATENT OFFICE

2,106,776

RECEIVING SYSTEM

Bertram Trevor and Ralph Waldo George, Riverhead, N. Y., assignors to Radio Corporation of America, a corporation of Delaware.

Application February 23, 1935, Serial No. 7,803

13 Claims. (Cl. 256—20)

The present invention relates to radio receiving systems, and particularly to systems which are adapted to receive ultra short wave energy.

One of the objects of the present invention is to provide a highly efficient and simple ultra short wave radio receiver.

Another object is to provide an improved radio frequency tuned oscillatory circuit having low loss.

10 A further object is to provide a receiver characterized by high frequency stability and capable of receiving signals having wide band modulation.

An important feature of the invention lies in the novel oscillatory circuit employed for resonating the received energy. More specifically, the oscillatory circuit comprises a low loss, radiationless, concentric arrangement having inner and outer concentric tubes which are coupled together at both of their adjacent ends. In the preferred arrangement there is provided, within the inner cylindrical tube, two spaced rods for receiving the collected energy, each rod being surrounded for a portion of its length by a hollow, concentrically arranged, cylindrical metallic element. An adjustable cylindrical ring located between the inner surface of the outer tube and outer surface of the inner tube serves to vary the constants of the oscillatory circuit. At one end of the inner conductor there is provided a lumped capacity in the form of a drum which couples this end with the outer conductor. The ends of the rods extend into this drum and thus have their potentials varied in accordance with the variations in potential of the capacity drum.

35 Another feature lies in the provision of a tuned circuit between the antenna and the concentric low loss oscillatory circuit for giving added radio frequency selectivity for the purpose of reducing the image response in the receiver. In the circuit embodiment hereinafter described, this tuned circuit comprises a pair of parallel wires conductively coupled together at one end and capacitively coupled together at their other end, but it is to be understood, of course, that any other type of tuned circuit such as a condenser, coil combination or another concentric low loss affair may replace the parallel wire tuned circuit.

50 Other objects and features will be apparent from a reading of the following detailed description which is accompanied by drawing, wherein:

Fig. 1 shows applicants' preferred embodiment of a complete radio receiving system, and

55 Fig. 1a shows a cross-sectional view of the con-

centric, low loss oscillatory arrangement of Fig. 1, along the lines A—A.

Referring to Fig. 1, modulated high frequency energy picked up upon antenna 2 is fed through transmission line 4 to the tunable trap circuit 6 having the adjustable tuning condenser 8. The transmission line 4 is variably connected or tapped to the sides 10, 12 of the tuned circuit 6 at points 14, 16, preferably so chosen that the impedance at points 14, 16 matches the surge impedance of the transmission line 4. The conductors 10, 12 of the tuned circuit 6 are substantially linear and are of low loss conductance as is also the bridging conductor 18 grounded at its midpoint by connection 20. At suitable impedance points 22, 24 on the tuned input circuit 6, the resonated energy from tuned circuit 6 is conductively fed on to metallic rods 26, 28 conductively connected to the end plate 30 of outer conductor 32. If desired, the resonated energy 20 from tuned circuit 6 may be capacitively fed to rods 26, 28. About rod 26 there is concentrically placed a metallic tube 34 conductively connected to the metallic end plate 30. Similarly, about rod 28 there is placed concentrically a metallic tube 36 also connected to the end plate 30. About both tubes 34, 36 is a further metallic pipe or tube 38 which is also in conductive connection with end plate 30. Slidably mounted about the tube 38 is a doughnut or cylindrical metallic end ring 40 which may be provided with ears 40' protruding through slots in the metallic walls 32, whereby the ring 40 may be moved at will along the tube 38. Preferably, ring 40 is in intimate frictional metallic contact with the inner surface of the outer conductor tube 32 and the outer surface of tube or pipe 38. The exterior of the outer conductor tube 32 is grounded, as shown.

Fig. 1a shows a cross sectional view of the low loss concentric tube oscillatory arrangement along the line A—A.

The collected energy after being resonated in tuned circuit 6 is fed through conductors 42, 44 to the rods 26, 28, in turn tuned by variable condenser 46. Variable condenser 46 is provided with a rotatable shaft 56, shown in Fig. 1 in dotted lines in turn linked to a knob 56' mounted in the front panel. The output of the circuit 26, 28, 46 is fed in phase opposition or in push-pull to the grids 48, 50 of detector tubes 52, 54.

The combination of tuned circuit 6 coupled with the two rod-like resonators 26, 28 and condenser 46 gives a band pass effect characterized by a flat top curve having steep sloping sides. This char-

acteristic gives an image response very much lower than a single resonant circuit.

At the right hand end of tube 38 there is mounted an inner drum 58, 60. The ring 40 is so adjusted that the capacity between the inner drum 58, 60 and the wall 32 and end plate 62 resonates with the inductance of the pipe 38 between the right-hand surface 64 of ring 40 and the inner drum end 60, at a desired frequency of operation for the local oscillation generator 66 the latter being provided with a suitably tuned plate circuit 68 also tuned to the desired local heterodyne frequency. Because of the low loss nature of the grid circuit of the local oscillation generator 66, its frequency remains substantially constant, and because of the nature of the grid circuit chosen and described, sufficiently high frequencies may be generated by the local oscillation generator 66 to suitably beat with waves picked up upon antenna 2, assumed, by way of example, to be of the order of frequency of 91.8 megacycles. For vernier adjustments of frequency a cylindrical vernier condenser 70 is provided, and for automatic frequency control, which shall be described more fully hereinafter, a further variable condenser 72 is provided.

The oscillatory circuit 64, 32, 60, 38, which is connected to the grid of local oscillator 66 at point 84, has its frequency determined by the length of 38 between walls 60 and 64 and the capacity between 58, 60 and 32, 62. Thus the frequency of this circuit can be varied by varying the length of 38, the capacity of vernier 70 and the capacity of vernier 72. In one embodiment successfully used, the capacity between drum 60, 58 and 62, 32 was approximately .0002 microfarad for a frequency of 80.3 megacycles.

It is preferred to have the side 64 of the doughnut ring 40 as near the side 60 as possible, in order to obtain a low L/C ratio, whereby the tuned impedance of the oscillatory circuit 64, 38, 60, 32 across point 84 and the cathode of local oscillator 66 is made as low as possible consistent with obtainable values of capacity between drum 60, 58 and 62, 32, so that the losses presented to the oscillatory circuit 64, 38, 60, 32 by the grid of local oscillator 66 will be as small as possible. In other words, it is desired to obtain as high a reciprocal of power factor (low loss) in the oscillatory circuit 64, 38, 60, 32 as possible, notwithstanding the loading imposed by the grid of local oscillator 66.

It should be noted that there is a smaller reciprocal of power factor on rods 26, 28 due to their smaller diameter than that of the oscillatory circuit 64, 38, 60, 32. Rods 26, 28 are purposely made longer than the length 38 located between sides 64 and 60 in order to build up an impedance as high as possible consistent with the resistance loading imposed by the grids 48, 50 of detectors 52, 54. At the desired dimensions, the resistance loading imposed by the grids 48, 50 will approximately match the impedance of rods 26, 28.

Electrically, oscillatory circuit 64, 38, 60, 32 is equivalent to the well known concentric, radiationless, low loss tuned circuit comprising inner and outer conductors conductively coupled together at one of their adjacent ends and capacitively coupled together at their other adjacent ends. For a more complete description of such an arrangement, reference is made to Reissue Patent No. 20,189, granted December 1, 1936, to Hans Otto Roosenstein, and to the application of Browder J. Thompson, Serial No. 746,124, filed September 29, 1934.

Sides 58 and 60 of the capacity drum have practically the same potential with respect to each other although the potential of the drum 58, 60 as a whole varies periodically at the frequency of local oscillator 66 with respect to ground or the outside wall 32. Consequently, that portion of the signal input circuit comprising rods 26, 28, which is within the drum 58, 60 will also vary periodically at the frequency of the local oscillator 66. It will thus be seen that the locally generated waves of oscillator 66 are fed to the grids 48, 50 cophasally or in push-push fashion, whereas the collected signal waves on rods 26, 28 are fed to these same grids 48, 50 in push-pull. In other words, there are two frequencies on rods 26, 28 which are supplied to the grids 48, 50 in different senses.

A tuned circuit 74 is provided for the output of the detector tubes 52, 54 and may be tuned, for example, to 11.5 megacycles when the local oscillation generator 66 is suitably tuned to produce such a beat with the 91.8 megacycle incoming wave picked up on the antenna 2. All the higher frequencies, such as the high beat frequency which is the sum of the two frequencies supplied to detectors 52, 54, the original signal frequency, and any oscillatory frequency due to unbalance in the plate circuit of the detectors are attenuated and thus prevented from entering the circuit 74 by means of choke coils 76, 78 aided by the by-passing effect of condensers 80, 82 so chosen in value as to offer relatively high impedance to the desired beat frequency energy appearing in circuit 74. Conversely, inductors 76, 78 offer a low impedance to the desired beat frequency, which is produced by plate rectification, but relatively high impedance to the higher beat produced during the heterodyning process. The entire outer surface 30, 32, 62 of the outer drum is at ground radio frequency potential and hence the cathode by-passing condensers may be connected directly thereto as shown in the drawing. The grid of the local oscillator 66 is connected to a point 84 on the inner drum surface 58, generation taking place by virtue of feedback 66 which will be found amply high for the wave lengths involved.

The inductance of the beat frequency output circuit 74 is formed by two coils 88, 90 effectively connected together for high frequency currents by condenser 92 and effectively grounded at that connection point through the intermediary of condensers 94. Symmetrically coupled to the coils 88, 90 is the coil 96 connected to transmission line 98 feeding the beat frequency energy into an intermediate frequency band amplifier 100. The output of amplifier 100 is fed into a further detector 102 supplied with local oscillatory energy from a suitable generator 104 and the lower beat output is suitably picked off and amplified in an amplifier 106. The mean frequency of the energy in amplifier 106 may be, for example, 460 kilocycles. The output of the amplifier 106 may then be fed into the succeeding amplifiers and detector equipment 107, from which the energy is supplied to a suitable recorder, such as a pair of headphones 108.

For automatically controlling the beat frequency of the oscillations obtained by beating the local oscillatory output with the oscillations obtained from the oscillatory circuit 26, 28, 46, a portion of the energy from detector 107 is supplied to frequency control apparatus 109, which is responsive to frequencies either side of the 75

mean or beat frequency to supply a potential current either to lead 110 or 111, so as to energize one of the coils 112 or 113, depending upon whether the frequency of the oscillations is to be increased or decreased, whereby armature 114, connected to continuously rotating telechron motor 115, is moved to the right or to the left.

Apparatus 109 may be of any type known in the art and preferably comprises relay equipment in the nature of a differential solenoid 116 and an electromagnetic device in the output of two electron discharge tubes 117, 118, whereby an increase in current through one tube will result in an increase in current through the upper portion of the solenoid and a decrease through the lower portion, or vice versa, causing the armature 119 to be moved upwardly or downwardly, as the case may be.

The movement of rotating armature 114 to its right position, for example, in response to the energization of coil 112, will cause the upper portion of 114 to engage with the inner circular ring 120 of concentric cam 121, thus causing cam 121 to rotate in one direction. If rotating armature 114 is attracted to the left by the energization of coil 113, then the upper portion of 114 will engage circular ring 122 and cause concentric cam 121 to rotate in the opposite direction to that caused when armature 114 engages ring 120. Since cam 120 is linked to variable condenser 72 by means of gears 123, 124, which are mounted on shafts 125, 126, respectively, it will be appreciated that condenser 72 will be automatically varied in a direction to compensate for frequency changes in response to variations in the beat frequency. Any change in position of condenser 72 will vary the capacity to ground between 72 and wall 60.

To assist the operator, there is provided a high-low frequency indicator 127 comprising a red lamp and a green lamp to indicate which way frequency compensation is being made by the automatic frequency control apparatus 109. A pair of electromagnetic relays 128, 129 are conductively connected at one of their ends to leads 110, 111 respectively, and at their other ends to ground, whereby the application of potential to one of the leads 110 or 111 will cause the energization of the associated relay 128 or 129 respectively to light the proper lamp over an obvious circuit.

Although the concentric tuned oscillatory circuit has been described with particular reference to an input stage, it is to be distinctly understood that the invention is not limited in this respect since the oscillatory circuit may also be used as an output coupling stage, if desired; such a coupling stage may be used between two succeeding electron discharge device circuits. It will thus be evident that various changes may be made in the form, shape and arrangement of the various elements of the invention to meet conditions encountered in their use without departing from the spirit and scope of the appended claims. It will also be understood that the concentric tubular inner and outer conductor arrangement is not limited to a conductive coupling at one end since a capacitive coupling at that end would also serve the purpose of the invention.

What is claimed is:

1. The combination with an ultra high frequency oscillatory circuit comprising inner and outer concentric tubular conductors which are coupled together at both ends, said conductors

being capacitively coupled together at least at one end, said capacitive coupling comprising a hollow metallic drum conductively connected to and mounted on said inner tubular conductor, of two spaced conductors within and separated from said inner tubular conductor, said spaced conductors extending into the interior of said hollow drum, whereby the potentials of said two spaced conductors vary in accordance with variations in potential of said hollow drum.

2. Apparatus in accordance with claim 1, including a hollow tube surrounding each of said spaced conductors and located within said inner tubular conductor.

3. The combination with an ultra high frequency oscillatory circuit comprising inner and outer concentric tubular conductors conductively coupled together at one end and capacitively coupled together at their other end, said capacitive coupling comprising a hollow metallic drum electrically connected to and mounted on said inner tubular conductor, of two spaced conductors within and separated from said inner tubular conductors, said spaced conductors extending into the interior of said hollow drum whereby their potentials vary in accordance with variations in potential of said drum, a high frequency input circuit, means coupling said input circuit to said spaced conductors near the ends thereof farthest removed from said hollow drum, an output circuit, and means coupling said output circuit to the other ends of said spaced conductors.

4. The combination with an ultra high frequency oscillatory circuit comprising inner and outer concentric tubular conductors conductively coupled together at one end and capacitively coupled together at their other end, said capacitive coupling comprising a hollow metallic drum electrically connected to and mounted on said inner tubular conductor, of two spaced conductors within and separated from said inner tubular conductors, said spaced conductors extending into the interior of said hollow drum and adapted to have potentials thereon which vary in accordance with variations in potential of said drum, a high frequency input circuit, means for adjustably coupling said input circuit to said spaced conductors near the ends thereof which are farthest removed from said hollow drum, an output circuit in the form of a pair of electron discharge devices having control grids, and means connecting said control grids to the other ends of said spaced conductors, said devices functioning to detect the energy on said spaced conductors.

5. The combination with an ultra high frequency oscillatory circuit comprising inner and outer spaced concentric tubular conductors conductively coupled together at one end and capacitively coupled together at their other end, said capacitive coupling comprising a hollow metallic drum electrically connected to and mounted on said inner tubular conductor, of two spaced conductors within and separated from said inner tubular conductors, said spaced conductors extending into the interior of said hollow drum and adapted to have potentials thereon which vary in accordance with variations in potential of said drum, a high frequency input circuit, means for adjustably coupling said input circuit to said spaced conductors near the ends thereof which are farthest removed from said hollow drum, said input circuit comprising another tuned circuit composed of a pair of parallel wires directly connected together at one end and capacitively cou-

pled together at their other end, and a connection individual to each of said wires and coupling same to one of said spaced conductors, each connection being individual to one of said spaced conductors, an output circuit in the form of a pair of electron discharge devices having control grids connected to the other ends of said spaced conductors, and means for suitably energizing the electrodes of said devices for enabling 10 same to detect the energy on said spaced conductors.

6. The combination with an ultra high frequency oscillatory circuit comprising inner and outer concentric tubular conductors conductively coupled together at one end and capacitively coupled together at their other end, said capacitive coupling comprising a hollow metallic drum electrically connected to and mounted on said inner tubular conductor, of two spaced conductors within and separated from said inner tubular conductors, said spaced conductors extending into the interior of said hollow drum and adapted to have potentials thereon which vary in accordance with variations in potential of said drum, a high frequency input circuit, means for adjustably coupling said input circuit to said spaced conductors near the ends thereof which are farthest removed from said hollow drum, said input circuit comprising another tuned circuit composed of a pair of parallel wires directly connected together at one end and capacitively coupled together at their other end, a pair of connections individual to and adjustably movable over each of said wires, each of said pair of connections comprising one connection coupled to an energy collector and the other connection coupled to one of said spaced conductors, and an output circuit in the form of a pair of electron discharge devices having control grids connected to the other ends of said spaced conductors, and means for suitably energizing the electrodes of said devices for enabling same to detect the energy on said spaced conductors.

7. A system in accordance with claim 6, including a variable condenser connected across said two spaced conductors at the ends thereof which are connected to said electron discharge device detectors.

8. The combination with an ultra high frequency oscillatory circuit comprising concentric inner and outer tubular conductors capacitively coupled together at one end and conductively coupled together at their other end, of a pair of spaced conducting rods extending throughout the length of and within said inner tubular conductor, a high frequency input circuit coupled to said rods near one end thereof and a detector circuit coupled to the other ends of said rods, means for enabling variations in potential of said inner conductor to produce corresponding variations on said pair of spaced rods, and an electron discharge device oscillator having a control electrode coupled to said inner conductor and a cathode coupled to said outer conductor.

9. The combination with an ultra high frequency oscillatory circuit comprising concentric inner and outer tubular conductors capacitively coupled together at one end and conductively or capacitively coupled together at their other end, of a pair of spaced conducting rods extending throughout the length of and within said inner tubular conductor, a high frequency input cir-

cuit coupled to said rods near one end thereof and a detector circuit coupled to said rods at or near the other end thereof, means for enabling variations in potential of said inner conductor to produce corresponding variations on said pair of spaced rods, and an electron discharge device oscillator having a control electrode coupled to said inner conductor and a cathode coupled to said outer conductor, and a frequency control circuit coupled to said detector circuit and responsive to variations in frequency about a mean value for automatically varying the capacitive coupling between said inner and outer tubular conductors in such direction as to compensate for the change in frequency.

10. In combination, an electron discharge device oscillator having tuned input and output circuits, said input circuit comprising a pair of concentric inner and outer hollow tubular conductors capacitively coupled together at one end and electrically coupled together at their other end, a pair of spaced conductors extending throughout the length of and located within said inner tubular conductor, means for enabling variations in potential of said inner conductor to produce corresponding variations on said last pair of spaced conductors, a condenser connected across one end of said spaced conductors, and means for supplying high frequency energy in push-pull to the other end of said spaced conductors, and a pair of electron discharge devices each having a grid, anode and a cathode, said grids being connected to said spaced conductors whereby energy from said last means is supplied to said grids out of phase and energy from said oscillator is supplied to said grids in phase, and a utilization circuit coupled to said anodes.

11. In an ultra shot wave heterodyne receiver, means for collecting radiated energy, a local oscillator, and a detector circuit coupled to said means and said oscillator for producing a beat frequency between said collected energy and the oscillations produced by said local oscillator, the coupling between said detector circuit and said means comprising two pairs of parallel conductors, each pair being directly connected together at one end and capacitively coupled together at their other end, and a connection from each conductor of one pair of parallel conductors to a conductor of the other pair.

12. A system in accordance with claim 11, characterized in this, that said connections between the pairs of parallel conductors are adjustably movable over said conductors.

13. An ultra high frequency oscillatory circuit comprising concentric inner and outer hollow conductors conductively coupled together at one end, a first metallic end plate covering the other end of said outer conductor, a second metallic plate conductively coupled to said inner conductor also at said other end and spaced from said first plate to provide a capacitive coupling therebetween, adjustable means between said inner and said outer conductor for varying said capacitive coupling, and means intermediate the ends of said conductors for adjustably coupling said conductors together at points along the lengths of said conductors.
